(57) **CLAIM**

The ornamental design for a digital kitchen timer, as shown and described.

DESCRIPTION

FIG. 1 is a front perspective view of an embodiment of a digital kitchen timer, showing my new design; FIG. 2 is a front elevation view thereof;

FIG. 3 is a rear elevation view thereof;

FIG. 4 is a left side elevation view thereof, with the right side elevation view being a mirror image thereof;

FIG. 5 is a top plan view thereof;

FIG. 6 is a bottom plan view thereof;

FIG. 7 is a front perspective view thereof, with the digital kitchen timer in a freestanding orientation; and,

FIG. 8 is a rear perspective view thereof, with the digital kitchen timer in a freestanding orientation.

The broken lines shown in the drawings depict portions of the digital kitchen timer that form no part of the claimed design.
